WALTER NEHLS, OF BERLIN-SIEMENSSTADT, GERMANY, ASSIGNOR TO WESTINGHOUSE ELECTRIC & MANUFACTURING COMPANY, A CORPORATION OF PENNSYLVANIA

DEVICE FOR CLEANING THE CATHODE MERCURY IN LARGE RECTIFIERS

Application filed May 26, 1928, Serial No. 280,783, and in Germany May 28, 1927.

My invention relates to mercury-arc rectifiers and it has particular relation to means for purifying the liquid mercury pool in large metal-tank rectifiers.

5 In metal-tank mercury-vapor rectifiers, it frequently happens that many foreign bodies or particles are deposited in the containers during operation, resulting in the contamination of the liquid mercury pool which constitutes the cathode, by reason of the washing down of the foreign bodies in the process of condensation of the mercury-vapor. By reason of their low specific weight, the foreign particles float on the surface of the cathode.

10 For this reason, various means have previously been adopted to separate the foreign particles from the cathode mercury and to collect them in a portion of the cathode where the arc cannot play.

15 The object of my invention is to maintain the purity of the cathode mercury pool in such manner as to avoid the difficulties and shortcomings of previous devices for this purpose, and, in particular, to provide an 20 external purifier or separating chamber which may be removed from time to time, as may be necessary for the purpose of cleaning, without disturbing the vacuum of the rectifier tank.

25 With the foregoing and other objects in view, my invention consists in the combinations and details of construction hereinafter more particularly described and claimed and illustrated in the accompanying drawing, 30 wherein—

Figure 1 is a vertical sectional view illustrating a metal-tank rectifier with my external purifier attached, and

Fig. 2 is a plan view thereof.

35 As shown in the drawing, my invention is applied to a rectifier comprising a cathode chamber 3 having liquid mercury 4 therein, and a main tank portion 5 which constitutes the arc chamber, supporting a plurality of anodes 6, and provided with a water jacket 7, or other cooling means, to constitute a condensing chamber 8, wherein the mercury vapor is condensed and returned eventually to the cathode.

40 According to my invention, the condensed

mercury is not returned directly to the cathode pool, and to this end, the cathode mercury is sub-divided by a tall insulating tube or cathode cup 10, into an active mercury-containing central space 11 and an annular inactive space 12 surrounding the same. The inactive space is closed at the top by a slanting annular cover 13, so that the used mercury which is condensed inside of the apparatus flows from the upper tank portion onto the 55 slanting annular cover 13 over the inactive portion 12 of the mercury and outside of the tall insulating cathode cup 10.

According to my invention, I have also provided means for withdrawing the condensed 60 mercury from above the inclined annular cover 13 and conducting it outside of the tank by means of a tube 15 which leads to a purifier or separating chamber 17 outside of the tank. In the purifier, the mercury has a 65 chance to stand still and the floating particles of foreign matter rise to the surface, after which the mercury is withdrawn again, from a point at which there are no impurities, by means of a second tube 18 which enters the 70 rectifier at a point below the annular cover member 13, thus discharging the mercury into the inactive space 12, from which it flows 75 underneath the cathode cup 10 into the active cathode space 11.

The two tubes 15 and 18 which lead to and from the purifier 17 are provided with detachable joints or couplings 19 and 20, respectively, whereby the purifier 17 may be removed, from time to time, for emptying and 80 cleaning. To this end, however, it is necessary to provide each tube with a vacuum valve 21, which may be closed prior to the opening of the couplings 19 and 20, so that the operation of the rectifier will not be disturbed during the brief interval when the purifier is 85 being cleaned.

The purifying of the mercury within the purifier or container 17 may be effected by 90 filter sieves or baffles or separators, or in any 95 other known manner. The essential feature of my invention is that the purification is done outside of the rectifier tank, in a vessel which can be removed without disturbing the 100 vacuum within the rectifier tank.

It will be noted that the condensed mercury is freed of its impurities before it is led back to the cathode, being tapped off, on its way to the cathode, and being caused to flow, by its own gravity, through a purifier which is disposed outside of the rectifier.

In large rectifiers, it will be understood that a plurality of purifiers may be arranged around the cathode periphery, preferably in a symmetric arrangement.

10 It will be understood that suitable evacuating openings and pumps will be provided, together with the necessary valves and control-indicating apparatus, as is customary in rectifiers. As such features are only conventional features of design, I have not deemed it necessary to illustrate the same.

While I have illustrated my invention in a preferred form of embodiment, it is to be understood that I am not altogether limited thereto, as many changes may be made by those skilled in the art, without departing from the essential features of my invention. I desire, therefore, that the appended claims shall be accorded the widest construction commensurate with their language and the prior art.

I claim as my invention:

1. An evacuated mercury-vapor rectifier of 95
30 the type in which the mercury vapor is condensed in an upper portion of the rectifier and returned to a mercury cathode pool in a lower portion thereof, characterized by having a separate purifier disposed outside of the
35 rectifier, partition means within the rectifier for trapping the condensed mercury as it flows toward the cathode pool, and pipes disposed above and below said partition means for leading the mercury to and from said
40 purifier as it flows, by gravity, into the cathode pool.

2. An evacuated mercury-vapor rectifier of 100
45 the type in which the mercury vapor is condensed in an upper portion of the rectifier and returned to a mercury cathode pool in a lower portion thereof, characterized by having a separate purifier disposed outside of the rectifier, partition means within the rectifier for trapping the condensed mercury as it
50 flows toward the cathode pool, pipes disposed above and below said partition means for leading the mercury to and from said purifier as it flows, by gravity, into the cathode pool, said purifier being detachably connected to
55 said pipes, and vacuum valves in said pipes.

3. An evacuated mercury-vapor rectifier comprising a mercury holder, a cathode mercury pool therein, a main tank thereabove including a plurality of anodes and a condensing space, an insulating cylindrical cathode cup dividing the mercury pool into a central active portion and an annular inactive portion, an annular cover member over said inactive portion and spaced thereabove, and a
60 purifying means for freeing the condensed
65

mercury of impurities as it passes from a position over said cover member to a position under the same.

In testimony whereof, I have hereunto subscribed my name this 9th day of May, 1928, 70
at Berlin-Siemensstadt, Germany.
